UNITED STATES PATENT OFFICE

EILET MARTIN-TORKELSON, OF ELIZABETH, NEW JERSEY

AIRPLANE

Application filed June 1, 1927. Serial No. 195,794.

This invention relates to airplanes and more particularly to novel automatic stabilizing means therefor.

To that end the invention contemplates a simple and practical means which may be readily set to automatically control a main stabilizing airfoil during flight of the airplane, and which will prevent the plane going into a stall and also preserve longitudinal stability by automatically varying the longitudinal dihedral angle.

A further object of the invention is to provide automatic stabilizing means which damps the oscillation of the tail of the plane, and also adjusts the stability to varying loads, as for example in the case of a bomb carrying plane when the bomb is dropped.

A further object of the invention is to provide a device which comprises a pair of airfoils pivotally mounted about different axes and adapted to have a differential movement which produces the desired correction.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings in which

Fig. 1 is a vertical sectional view of the tail of an airplane embodying the present improvements.

Fig. 2 is a top plan view of the construction shown in Fig. 1.

Fig. 3 is a vertical sectional view taken on the line 3—3 of Fig. 1.

Fig. 4 is an enlarged detail sectional view illustrating the pivot axis of the main stabilizing airfoil and part of the controlling means for the auxiliary airfoil.

Fig. 5 is a diagram illustrating the theoretical operation of the main and auxiliary airfoils.

Fig. 6 is a diagram illustrating the rela-

tive angular movement of the main and auxiliary airfoils.

Fig. 7 is a diagram illustrating the manner of determining the downwash angle.

Fig. 8 is a side elevation of an airplane embodying the present improvements.

Similar reference characters designate corresponding parts throughout the several figures of the drawings.

Ordinarily the majority of airplanes have a horizontal rudder or stabilizer subject to the control of the pilot and adapted to be manually manipulated to vary the longitudinal dihedral angle to preserve longitudinal stability.

However, it is the object of the present invention to render the stabilizing airfoil automatic in its operation thereby relieving the pilot of the necessity of continuously manipulating the same. In other words during the course of flight the automatic means provided will manipulate the main stabilizing airfoil without manual attention, and in proportion to the deflection of the plane from its normal course, once the initial angle of the auxiliary airfoil is set by the control stick.

Accordingly, as will be observed from the drawings, the present invention includes in its organization a main stabilizing airfoil A arranged at the tail of the fuselage of the airplane, and an auxiliary controlling airfoil B mounted on a bracket or lever arm C carried by the main airfoil and extending forwardly toward the wing positions of the airplane. The said arm C is arranged at the central part of the main airfoil A between the vertical fins D which are aligned with the vertical rudders E.

The main stabilizing airfoil A is preferably pivotally supported on the fuselage of the plane by a pivot axle 1 or its equivalent mounted in the journals 2 thereby to permit the airfoil to have a rocking movement in the usual manner to correct the longitudinal line of flight of the machine. As previously indicated, the bracket arm C is rigidly connected to the medial portion of the main stabilizing airfoil A and extends upwardly and forwardly at a suitable angle and piv-

totally receives or carries the controlling airfoil B. The said airfoil B is mounted on a rockable pivot 3 in the arm C and is provided adjacent the arm with a pulley 4 which receives a belt, chain or its equivalent 5 that leads to the relatively small pulley portion 6 of the main control pulley G loosely mounted on the pivot shaft 1. The pulley portion 7 of larger diameter receives 10 an adjusting cable, rope, chain or equivalent 8 which is looped thereabout and passes over the direction controlling pulleys 9-9 mounted on the bottom of the fuselage and has its ends connected to the terminals 10 and 11 15 of the control lever 12.

In the normal use of the present stabilizing device, which includes the main stabilizing airfoil A and the auxiliary airfoil B located in front thereof and in the path of the downwash from the main wings of the plane, the said auxiliary airfoil B, having been set to the desired position by the pilot, tends to always assume a position which is governed by the downwash of the front 25 wings regardless of the movement of the plane. Thus, the auxiliary plane moves or operates the main stabilizing airfoil up or down to shift the plane into its normal position. The main airfoil A and auxiliary 30 airfoil B are connected by an arm which is integral with the airfoil A, moving with it, while the airfoil B is connected to the arm through a pivot. It is therefore apparent that merely the angular rotation of the airfoil B about its pivot is the only operation controlled by the stick in the cock pit. Although the airfoil B is smaller than the main airfoil A, the airfoil B will control the airfoil A through an angular motion about 35 its pivot, due to the tremendous leverage exerted by means of connecting arm, the larger airfoil A also being more or less balanced on its pivot at the return of the ship structure. The airfoil B always has the tendency to remain in a position which will have its angle neutral to the downwash angle from the front main wings whatever that may momentarily happen to be. It is therefore apparent that should the downwash vary, 40 either through a change in air currents, or in the lightening of the load of the ship, this momentary change of the downwash angle will tend to move the auxiliary plane B through a distance according to its initial 45 angular setting and so control the rear airfoil A by exerting a torque against it of the relatively long connecting arm.

If the pilot intends to follow a horizontal course after gaining his altitude he manipulates the control lever 12 to set the auxiliary controlling airfoil B in the proper position to keep the plane on a horizontal course. In that connection the horizontal axis of the airfoil B may or may not be parallel with 50 the axis of the airfoil A. In the arrange-

ment shown in the drawings there will always be a slight download on the auxiliary airfoil B to balance the horizontal component of force on the airfoil A. If the plane strikes bumpy air or attempts to go into a stall, the auxiliary airfoil B will be moved by the increased pressure due to additional resistance encountered and proportionately move the main stabilizing airfoil thereby to bring the plane back into the path of normal flight. 70

Having described the general structural features and characteristics of the invention, reference will now be made to the theory and application of the invention from a technical standpoint. 75

Referring to Fig. 5, since the main airfoil A and the pulley 6 have the same axis, they will both be referred to as the pulley A-6. From this figure of the drawing it will be observed that A-6 representing the main airfoil and pulley 6 are located at one end of the lever C which carries at its outer end the auxiliary airfoil B and pulley 4. Each pulley 6 and 4 is free to move on its center and also lever C may move about the center of airfoil A. The non-slipping belt is placed around pulley 6 and 4 as previously described, and it will also be remembered that the pulley 6 associated with the main airfoil A has twice the diameter of pulley 4 associated with auxiliary airfoil B. The sections of the belt indicated as d-e and f-g are tangent lines to both pulleys 4 and 6. According to geometry the radii O-d, O'-e, O-f, and O'-g are perpendicular to the lines d-e, and f-g respectively. Therefore the lengths d-e and f-g cannot be changed. Suppose for example pulley 6 is caused to be stationary on its center and the lever C is moved up through an arc of 15° about the pivot O. Lines f-g and d-e are at a constant angle to lever C. Therefore, when lever C is moved through 15° these two lines also move through 15°. Now by the same rule radii O-d and O-f move through 15° because they are always perpendicular to tangent line at point of tangency. Since pulley 6 is held stationary, the length of belt equal to the arc d-d' is removed, from the tangent line below, and likewise arc f-f' is added to the tangent line above, but being that the length of these lines are constant, and equal, it means that a length of belt equal to arc 100 f-f' or d-d' must run over the pulley 4 when the lever C is moved up through 15°. The angle through which the airfoil B and pulley 4 rotates depends upon the ratio of its diameter to the diameter of fixed pulley 110 A. In this case when lever C is moved through 15°, airfoil B must rotate through 115 30°.

If pulleys 4 and 6 were of the same diameter, airfoil B would always remain parallel 120

to the same line throughout the range of the movement of lever C for any single position of the stationary pulley. The construction would not function properly if the 5 pulleys were of the same diameter because a change in angle of downwash giving airfoil B a positive lift, would have the same effect at all positions of the lever arm C and hence it would merely rise up until it was stopped by structural interference and stay 10 there.

However, with the pulley 4 half the diameter of pulley 6, the auxiliary airfoil reaches its limit of effectiveness or maximum lift 15 with opposite inclinations at the same time airfoil A does, assuming the bubble point to be around 16° . The auxiliary airfoil B will always move through the same angle as airfoil A, in reference to the body of the 20 airplane, (see Fig. 6). As the downwash angle of airstream varies for any reason, the airfoil B is placed at an incidence to the airstream causing it, with lever C to be deflected either up or down as the case may 25 be but due to the planetary motion of airfoil B, caused by its flexible connection with the now fixed pulley G, it turns counter to lever arm C until it is again neutral or stable to the downwash airstream.

30 The downwash angle is the angle through which the airstream is deflected by any lifting surface of an airplane. The angle of downwash from the main planes is approximately one half the angle of incidence of the 35 main planes measured from angle of no lift.

By way of illustrating an example, reference may be made to Fig. 7 of the drawings and the following table. This table would 40 vary for different wing shapes, as the wings may be set at a different angle and also the neutral lift line may be different.

Angle of wing to wind in degrees...	0	2	4	6	8	10	12	14
Angle of body axis to wind.....	-4	-2	0	2	4	6	8	10
Angle of downwash relative to body axis.....	-5	-4	-3	-2	-1	0	1	2

45 horizontal flight position.

The downwash angle is an index, of the flying condition and attitude of the airplane.

This variation of the airstream furnishes 50 the corrective force, which moves the auxiliary airfoil and by its fixed lever connection rotates the balanced stabilizing airfoil A.

Now suppose we have an airplane whose 55 wings have a fixed setting of four degrees and a neutral lift line at -2° degrees the same as indicated in Figure 7. We are flying horizontally. The control lever is so set that both A and B airfoils are neutral 60 or stable to the downwash airstream or are inclined at three degrees to body axis of plane. Now if the plane by reason of the rough air is precipitated into a position so that the wings are at an angle of 10 degrees 65 to the wind, a change will take place in the

downwash from -3° degrees to 0° degrees which places airfoil A and auxiliary airfoil B at an incidence of 3° degrees to downwash airstream. Airfoil B, responds to this lift therefore the lever arm C now moves up 3 degrees placing airfoil A at 3° degrees additional incidence to airstream, and airfoil B turns down 6° degrees relative to arm C placing it neutral to the downwash airstream. The resulting lift of the 6° degrees incidence of airfoil A will raise the tail of plane back to normal at the same time the downwash angle returns to normal, causing the lever arm C to resume its original position. The device will operate in similar manner when the tail is inclined upward from the nose of the airplane.

Assuming that the stabilizing plane A is fixed so it does not rotate, this change of incident angle will impress a righting moment on tail of airplane and tend to bring it back to normal. This tendency is known as static stability and is the method by which airplanes usually are stabilized. These righting moments will however set up oscillations caused by the over running of the righting moment and by the constant shifting of the center of pressure of the wings. An airplane will be dynamically stable only if these oscillations diminish with time and ultimately die out.

The righting moment impressed upon the tail by the automatic adjustment of airfoil A will be twice as great as it would be if airfoil A was fixed in reference to body axis. (Referring to case above where A is 6° degrees incidence instead of 3° degrees).

This ratio is dependent upon the relative sizes of the two pulleys. Owing to the fact that the total control surface from which longitudinal stability is derived, adjusts its self to oppose any oscillatory movements and, that the moment of inertia of airfoil A with its attached lever and airfoil B, about its axis, is so small compared to the forces acting upon airfoil B, that it will have no tendency to overrun, making great dynamic stability possible by quickly damping out oscillations of tail.

The question of stability is closely connected to controllability. An airplane possessing a large amount of inherent stability is sometimes difficult to control, or in the words of the pilot, is said to be heavy on the controls. The automatic stabilizer however will give great inherent stability but being the movements of the main stabilizing plane is controlled by indirect means, its manipulation will be easy.

Therefore the actual function of control lever 12 is to select the angular setting of lever arm C at which airfoil B is neutral or stable to the downwash airstream, serving the same purpose as the conventional elevator control. The automatic feature of

the device makes it possible to fly at any attitude desired. If the power is reduced for any reason, such as motor failure in multimotored plane, by setting lever 12 back, horizontal flight will still be possible at a reduced speed.

This will not require the constant attention of the pilot as is usually the case with ordinary elevator control. The attitude can 10 be held so that the wings will assume an angle very near the burble point giving maximum lift and minimum speed which will reduce the hazards and required skill in both taking off or landing.

15 One of the principal causes of serious accidents with airplanes is the stall, which is the condition of an airplane when from any cause it has lost the air speed necessary for support or control. This device eliminates the stall by turning the nose of the plane down for independently increasing the air speed when it is approaching the stalled condition, thus avoiding the nose dive caused by the wings losing lift due to the fact 20 that the angle of attack is beyond the burble point. This device can be so arranged that it would be impossible to place plane in a stalled condition voluntarily. In cases 25 where air conditions are severely turbulent 30 the device will always operate in a way to give control and horizontal or gliding flight in an upright position.

Without further description it is thought 35 that the features and advantages of the invention will be readily apparent to those skilled in the art, and it will of course be understood that changes in the form, proportion and minor details of construction may be resorted to, without departing from 40 the spirit of the invention and scope of the appended claims.

I claim:—

1. In an airplane, the combination with 45 a main wing of automatic stabilizing means comprising a main airfoil pivotally mounted at the tail of the fuselage, a centrally disposed arm projecting from the forward end of the said main airfoil, an auxiliary airfoil having its medial portion pivoted in 50 said arm and located in the path of the downwash from said wing, a double pulley member loosely journaled coaxially with the pivot of the main airfoil, a flexible connection between said pulley and the pivotally 55 mounted auxiliary airfoil, a manually shiftable lever, and flexible means controlled by said lever and passing over another portion of said double pulley.

2. In an airplane the combination with a 60 main front wing of the airplane, of a rear pivoted airfoil, an arm carried by said airfoil and projecting upwardly and forwardly from the axis of said airfoil, a controlling airfoil pivotally mounted at the front end of 65 said arm and adapted to have a differential

arcuate movement from said rear pivoted airfoil, and manually operated means for said controlling airfoil to thereby render the said rear pivoted airfoil responsive automatically to the movement of the auxiliary 70 airfoil.

In testimony whereof I hereunto affix my signature.

EILET MARTIN TORKELSON.
